CIGARETTE EXTINGUISHER

Daniel F. Norton, Chicago, Ill.

Application February 18, 1935, Serial No. 6,996

2 Claims. (Cl. 131—51)

The object of this invention is the production of a cigarette extinguisher that will put the fire out on a given cigarette quickly, without crushing, fumes, fire hazard and in a sanitary way. This cigarette extinguisher may be fixed or attached to any ashtray, and it may be detachable or it may be firmly fixed to the tray.

One form of the invention is illustrated in the accompanying drawing, in which:

10 Fig. 1 shows a view wherein there are two extinguishers mounted on an elevated base #2.

Fig. 2 shows in side elevation the tube of an extinguisher with an opening therein to allow ashes to fall through into the tray.

15 Any number extinguishers may be set up on a given ashtray. They may be set up on an elevated base as shown in Fig. 1, or affixed to the bottom of an ashtray without an elevation.

20 As shown in Fig. 1, #1 shows the extinguishers; #2 shows the base; #3 shows a screw with which the fixture is fastened to an ashtray; #7 shows tray #6 drawn up for mounting base #2; #4 shows the bell shaped or restricted opening which receives the cigarette and #5 shows the opening through which ashes fall through to the tray.

25 Fig. 2 #1 shows an extinguisher tube in a vertical position, the more clearly to illustrate the opening #5 through which ashes fall into the tray.

30 The desired result of the invention is accomplished by inserting the lit-end of the cigarette downwardly into the tube until the upper end of the tube is closed, thereby cutting off the supply

of oxygen which tends to pass around the outside of the cigarette, and thus choking the fire within ten seconds more or less. The lighted end of the inserted cigarette is usually disposed adjacent the upper end of the opening 5. The ashes thus fall through the opening directly into the tray and do not accumulate in the lower portions of the tubes which would necessitate removal of the same from time to time.

10 I claim:

1. A device of the character described, comprising in combination, an ashtray and an extinguisher mounted thereon, said extinguisher comprising an inclined tapering tube, having a constricted portion adapted to receive and extinguish a lighted cigarette and provided in its lower side wall beneath said constricted portion with an elongated opening through which ashes from the interior of the tube pass directly into the tray.

20 2. A cigarette extinguisher comprising a tray, an internally tapered tube carried by and inclined with respect to said tray, said tube being open at the upper end and provided with an opening in the lower side thereof and having an internal 25 diameter adjacent the upper portion of said opening such that a lighted end of a cigarette inserted through said open end is engaged by the walls of the tube adjacent the upper end of said opening to snuff the fire and enable the ashes to drop from said tube through said opening.
